United States Patent Office

Des. 231,543

Patented Apr. 30, 1974

231,543

RATTLE

Jorma Vennola, Princeton, and Erkki Pekka Korpilaakko,
Hightstown, N.J., assignors to Columbia Broadcasting
System, Inc.

Filed July 12, 1972, Ser. No. 270,982

Term of patent 14 years

Int. Cl. D21—01

U.S. Cl. D34—15 AG

FIG. 1

FIG. 2

FIG. 3

FIG. 4

FIG. 1 is a perspective view of a rattle showing our new design;

FIG. 2 is a back plan view;

FIG. 3 is a front plan view; and

FIG. 4 is an end elevational view.

We claim:

The ornamental design for a rattle, substantially as shown.
